Augustus W. Newell

United States Patent Office.

AUGUSTUS W. NEWELL, OF BRADFORD, PENNSYLVANIA.

Letters Patent No. 72,530, dated December 24, 1867.

IMPROVEMENT IN STEAM-GENERATORS.

The Schedule referred to in these Letters Patent and making part of the same.

TO WHOM IT MAY CONCERN:

Be it known that I, AUGUSTUS W. NEWELL, of Bradford, in the county of McKean, and State of Pennsylvania, have invented a new and useful Improvement in the Manufacture of Boilers for Generating Steam; and I do declare that the following is a true and accurate description thereof, reference being had to the accompanying drawings, and to the letters of reference marked thereon, and making a part of this specification.

The objects I have in view in the construction of a boiler, as hereinafter described, are several. Among them may be enumerated the following:

First, by constructing a boiler in sections it is much more easily transported and set.

Second, the tendency to explosion is materially lessened, if not almost entirely obviated.

Third, in case of explosion the damage will be comparatively light, as, if the sections are properly constructed, the one which explodes will be the only section materially injured.

Fourth, should it be necessary to repair the boiler at any time, the section needing such repairs may be easily taken out and sent to the repair-shop, if required, saving the expense and trouble of taking out and transporting the whole boiler.

Fifth, by removing one or more sections, if too much boiler-room is had, the expense of taking out and cutting off the boiler is done away with.

Sixth, if more boiler-room is at any time required, it can easily be had by adding one or more sections, as may be necessary.

Seventh, the heating-surface of the boiler is more than quadrupled, thereby effecting a great saving in fuel.

Eighth, by the admission of air through appropriate apertures between the sections, combustion is greatly increased and the gases consumed.

Ninth, the remaining sections, when one or two sections are removed for repairs, may be used, preventing the necessity of stopping work.

My invention consists in constructing a boiler in sections, with heads at each end of each section, with or without flues, as may be most desirable. These sections can be made to go together with telescopic joints, or there may be placed upon them proper lugs, which, when bolted together, will hold the sections firmly in place. Each section is a separate and distinct boiler in itself, with its appropriate steam and feed-pipes and blow-off cock. The joints of the steam and feed-pipes should be fitted with expansion-joints to allow for contraction and expansion. In setting these sections, they should be placed end to end, so that the flues will be opposite each other in each section. By so setting the sections, a space will be left between the heads for heating purposes, and into these spaces there should be openings to admit the outer air, by which means the combustion will be greatly increased and the gases consumed.

Having thus described the objects and construction of my invention, which I make of rolled metal, I will now name the various parts that are so accurately shown in the drawing, so that those skilled in the art can manufacture the sectional boiler.

The drawing is partially in section. A' A A A are sections as hereinbefore described, A' being shown unattached. B B B are lugs to hold the sections together. C C C are steam-pipes, fitted with D D D, expansion-joints. F F F are openings for the admission of air into the spaces between the sections. E E are flues.

What I claim as my invention, and desire to secure by Letters Patent, is—

1. The apertures F F F, &c., between the sections, for the purpose set forth.
2. The combination and arrangement of the sections A A, &c., the lugs B B, &c., or their equivalents, the steam-pipes C C, &c., provided with expansion-joints D D, &c., or their equivalents, and the apertures or openings F F, &c., when constructed substantially as and for the purposes described.

AUGUSTUS W. NEWELL.
